CLAIM

The ornamental design for a "metering device" as shown
and described.

DESCRIPTION

FIG. 1 is a front right perspective view of a body of a
metering device.

FIG. 2 is a front view of the body of the metering device of
FIG. 1.

FIG. 3 is a right side view of the body of the metering device
of FIG. 1.

FIG. 4 is a left side view of the body of the metering device
of FIG. 1.

FIG. 5 is a top view of the body of the metering device of
FIG. 1.

FIG. 6 is a bottom view of the body of the metering device
of FIG. 1.

FIG. 7 is a front right perspective exploded view of the
metering device of FIG. 1.

FIG. 8 is an alternate front right perspective exploded view
of the metering device of FIG. 1; and,

FIG. 9 is an alternate front right perspective exploded view
of the metering device of FIG. 1.

(Continued)

The broken lines shown are included for the purpose of illustrating portions of the metering device and form no part of the claimed design.

1 Claim, 6 Drawing Sheets
